UNITED STATES PATENT OFFICE.

HARLIE O. PUTT, OF ELKHART, INDIANA.

CONVOLUTE AMPLIFYING HORN.

Application filed May 15, 1924. Serial No. 713,584.

The object of my invention is to provide a novel convolute amplifying horn for use with radio apparatus and phonographs. It is an essential object of my invention to provide a horn which will take up little space, but which is highly efficient in amplifying sound waves, and which is also artistic in appearance. I attain these and other objects of my invention by the device illustrated 10 in the accompanying drawings, in which:

Figure 1 is a side elevation of one form of my invention;

Fig. 2 is a vertical section on line 2—2 of Fig. 1;

Fig. 3 is another form of my invention; and

Fig. 4 is a vertical section on line 4—4 of Fig. 3.

Like numerals indicate like parts in each 20 of the several views.

Referring to the accompanying drawings, I provide a convolute amplifying horn preferably formed of a plurality of sections, 1 and 2, suitably secured together, as by the 25 screws 3 to provide a convolute amplifying passage 5 terminating in the mouth 6, as shown in Figs. 1 and 2. I provide a sound-conveying or tone-tube 7 opening into the small end of the convolute passage at 4, and 30 provide opposite enlargements 9 and 10 in the portions of the horn through which tube 7 passes. Tube 7 preferably projects through the horn and furnishes a means for mounting the same in connection with the dia- 35 phragm D, as shown in Fig. 1. While the enlargements 9 and 10 are provided in order to reduce the restriction of the tone chamber by the disposition of the tube 7 therethrough, the provision of these enlargements will be 40 necessary only in the smaller sizes. In the larger sizes the cross-sectional area of the tone chamber or passage will be great enough to accommodate the tube 7 without serious hindrance to the passage of the tone-waves.

45 The tube 7 may be positioned either as shown in Figs. 1 and 2, or may radiate in any desired direction from the center or small end of the amplifier. The usual bell-shaped flare is preferably formed separately and 50 suitably attached to the large opening or mouth 6.

Another form of my invention is disclosed in Figs. 3 and 4, in which the amplifying

horn is preferably formed of two sections 11 and 12. At the small end 13 of the passage 55 14 I provide a short lateral sound conveying tube 16 mounted in portion 17 of the horn and communicating with the diaphragm D, as shown in Fig. 4. I preferably provide a suitable base 18 on which the horn is 60 mounted, as shown in Figs. 3 and 4. The horn terminates in a bell-shaped mouth 15 preferably aligned with the exterior surface of the adjacent convolution of the horn, and 65 preferably formed integral therewith.

The point of juncture throughout the convolutions when the horn is made in two sections, as shown in Figs. 2 and 4, as well as the fit of the tubes 7 and 16, must be airtight.

It is within the contemplation of my invention to cast or mold the horn in one piece by utilizing a suitable removable or collapsible core, or to provide a horn of stamped or pressed metal or other suitable material or composition.

It is also within the contemplation of my invention to construct my amplifying horn with a circular, elliptical or square cross section. The preferred construction is to mold, cast, or press the material into the 80 desired form.

By constructing an amplifying horn as above described, I provide an amplifying mechanism having great acoustical value, occupying the smallest possible space, and 85 one which can be readily and cheaply manufactured by means of suitable molds, patterns or dies. An amplifying horn of this type may be constructed of cement or concrete on a comparatively large scale for outdoor utilization.

An amplifying horn such as I have described is rigid and non-vibrating and adapted to a wide variety of applications, such as public speaking systems, radio receiving sets, phonographs, etc.

What I claim is:

The combination of a convolute amplifying horn, a tone-tube communicating with the small end of the horn passage, the portions 100 of the convolutions of the horn adjacent to the said tone-tube being enlarged to prevent restriction of the passage at this point the tone-tube extending through the convolutions.

HARLIE O. PUTT.
